TYPE BED

Edd C. Oliver, Adrian, Mich.

Application September 10, 1934, Serial No. 743,424

6 Claims. (Cl. 101—380)

This invention relates to type beds and the object of the invention is to provide a type bed having spaced parallel grooves and provided with type holding bars insertable in the spaced grooves 5 to hold the type therebetween.

Another object of the invention is to provide a means for holding the type under pressure at the base so that the type will remain in fixed position and cannot be readily moved in the normal 10 printing operations.

A further object of the invention is to provide a type bed having spaced grooves therein into which type holding bars may be inserted to provide spaced parallel ribs between which rubber 15 type may be mounted, the type being slightly wider at the base than the distance between the adjacent sides of the type holding bars.

Another object of the invention is to provide a type bed in which sheet metal type holding bars may be inserted to hold the type, the sheet metal 20 type holding bars being provided with yieldable flanges in order to firmly hold the type therebetween.

A further object of the invention is to provide a means for yieldably holding solid non-compressible type on a type bed in printing position. 25

These objects and the several novel features of the invention are hereinafter more fully described and claimed and the preferred form of construction by which these objects are attained 30 is shown in the accompanying drawing in which—

Fig. 1 is a plan view of a type bed embodying my invention.

Fig. 2 is an enlarged section taken on line 2—2 of Fig. 1.

Fig. 3 is a perspective view of the type holding bar which is inserted in the grooves of the type bed.

Fig. 4 is a sectional perspective showing a modified form of type holding bar for holding the type in position.

Fig. 5 is a similar section showing another modified form of type holding bar.

Fig. 6 shows the type holding bar of Fig. 5 in inverted position.

Fig. 7 is a section showing the simplest form of type holding bar and groove.

The type bed may be made of any suitable material, the cheapest form being laminated wood, fibre or solid wood as suggested in Fig. 2. This type bed 1 is usually rectangular in form and is provided with spaced parallel grooves 2 shown in Figs. 1 and 2. The type holding bar is shown more particularly in Fig. 3 and comprises a metal bar 3 having sloping sides which slope toward

the center as shown. These bars may be equal in length to the width of the type bed and are inserted in the grooves 2 as shown in Fig. 2. The grooves 2 are all equally spaced lengthwise of the type bed and the type holding bars may be inserted in different grooves to take type of different widths. For instance, the smallest type to be used may be one-half inch. The next size type may be one inch wide plus the width of the intervening groove and the next size may be one 10 and one-half inches or two inches wide plus the width of the intervening grooves; the various type being formed in multiples of the space between the bars plus the width of the intervening 15 grooves.

In this case, the narrowest type 4, shown in Fig. 2, is held by the type bars 3 positioned in two adjacent grooves, while the type 5 is held in place by positioning the next type holding bar in the second groove, as shown, while the type 6 is held by placing the type holding bar 3 in the third groove so that the intervening grooves 2 are spanned by the type as shown at the right of Fig. 2. These type holding bars are provided with sloping or under-cut sides as shown and the type 25 is slightly wider than the distance between the upper edges of the adjacent type holding bars so that it is necessary to press the type into the space between the type holding bars and as the rubber is under compression the type is firmly held in place. It will also be noted that the rubber type expands beneath the under-cut edges of the type holding bars which prevents the type 30 from being pushed over in the inking or printing operations. The under-side of the type bed 35 may be also provided with longitudinal grooves 2a as shown in dotted lines in Fig. 2 which are of the same form as the grooves 2 but extend longitudinally of the type bed in case it is desired to reverse the type bed and set the type longitudinally of the type bed. In this case, the spacing 40 of the grooves would be the same as shown in full lines in Fig. 2.

It is also possible to make the type holding bar from sheet metal as suggested in Fig. 4 in which case the bar is rolled to approximate U-form with sloping sides to simulate the contour of the bar 3.

In this case, however, the sloping flanges 7 of the type holding bar may be readily sprung inwardly when held in the grooves 2, as shown in Fig. 4, and consequently by this arrangement a wood base or solid base type 8 may be used having grooves 9 in the opposite sides thereof in which the flanges 7 of the type holding bars may en- 55

gage. By this arrangement, the solid base type may be pressed against one of the flanges 7 until it will clear the flange 7 of the next type holding bar, at which time, it may be pushed down to position on the type bed and the metal flanges 7 will hold the solid base type in place.

Another alternative form of sheet metal type bar is shown in Fig. 5 in which the sheet metal is formed to provide a C-shaped portion 10 having two outwardly and angularly extending flanges 11. The portion 10 may be inserted in the groove 2, as shown in Fig. 5, and the flanges 11 will engage in the grooves 9 on opposite sides of the type bases. This form, shown in Fig. 5, may be also reversed or inverted by inserting the flanges 11 in the groove 2, as shown in Fig. 6. In this case, the portions 10 extend upwardly so that rubber type 12 may be engaged therebetween. The type holding bar shown in Fig. 4 may also be inverted in the same manner for holding rubber type and will then have substantially the outer surface contour of the type holding bar 3 above the groove 2. For holding solid base type, such as wood block or solid metal bases, the sheet metal type bars are positioned with the spring flanges extending upwardly so that the solid base type may be firmly engaged therebetween by providing grooves in which the spring flanges engage, while with the compressible type, such as rubber base type the type holding bars may be inverted and need not be compressible as the type itself may be compressed into the space between the bars.

The simplest form of type holding bar and groove is shown in Fig. 7 in which a metal bar 15 is provided which is rectangular in cross section and fits in a rectangular groove 16 in the type bed 1. This type holding bar will retain the type in position and may be inserted in the top of the type bed rather than from the edge, if desired, and while it may not hold the type as firmly as the other forms of type holding bars, it may be used with good results under normal conditions.

The sheet metal form of type holding bar as suggested in Figs. 4, 5, and 6 has a flexible wall permitting the type to be introduced therebetween by pressing the side wall of one type bar in a direction away from the adjacent type holding bar permitting an insertion of the type therebetween. Either the rubber form or the solid unyieldable form may be used. Such latter form is preferably grooved to receive the edge of the sheet metal holding bars as more particularly shown in Fig. 5. Rubber type may be used with this character of type holding bar and they may be shaped of greater width at the base than between the contacting edges of the type holding bars. Whenever occurring in the appended claims, the term "flexible type holding bars" refers to a form of bar such as shown in Figs. 4 to 6 in which a wall or flange of the type bar is capable of being flexed toward its companion wall.

From the foregoing description it becomes evident that the device is very simple and efficient in operation, will not easily get out of order, provides an easy and simple arrangement for mounting type on a type bed and provides a device which accomplishes the objects described.

Having thus fully described my invention, its utility and mode of operation, what I claim and desire to secure by Letters Patent of the United States is—

1. In a type bed, a flat bed member provided

with a series of grooves opening through a face and opposite side edges thereof, the grooves being of less width at the opening through the face than at the base, a series of type holding bars insertable in the grooves, each type holding bar being formed from sheet metal and being provided with spring flanges extending upwardly from the grooves above the surface of the type bed, the bars being of less width centrally between the opposite parallel faces and insertable endwise in the grooves with the narrow intermediate portion practically aligning with the opening of the groove in the face of the bed and providing a type space therebetween of greater width at the face of the bed than the width between the edges of the bars thereabove, a series of type of greater width at the base than the normal distance between opposite edges of the type holding bars positioned between adjacent type holding bars, each type being provided with a groove to receive the spring flange of the adjacent type holding bar.

2. In a type bed, a flat bed member having a series of grooves opening through a face and opposite side edges thereof, the grooves being of less width at the opening through the face than at the base, a series of type holding bars insertable in the grooves, each type holding bar being formed from sheet metal and being provided with spring flanges extending upwardly from the grooves above the surface of the type bed, the bars being of less width centrally between the opposite parallel faces and insertable endwise in the grooves with the narrow intermediate portion practically aligning with the opening of the groove in the face of the bed and providing a type space therebetween of greater width at the face of the bed than the width between the edges of the bars thereabove, a series of type of greater width at the base than the normal distance between opposite edges of the type holding bars positioned between adjacent type holding bars, each type being provided with a groove to receive the spring flange of the adjacent type holding bar.

3. In a type bed, a bed member provided with a series of grooves of greater width at the bottom than at the opening through the face of the bed, a series of sheet metal type holding bars of substantially U-form in cross section, said bars being of greater width at the opposite parallel edges than the width intermediate the same permitting either edge to seat in a groove, the type holding bars being insertable in the grooves with the upper edges thereof extending above the grooves, the sides of the type holding bars being yieldable when so positioned and a series of type engaged between the adjacent sides of the adjacent type holding bars and resting on the type bed, said type being of greater width at the base than the distance between the adjacent sides of the type holding bars.

4. In a type bed, a bed member having a series of spaced parallel grooves in its opposite side faces, the grooves in one face lying at a right angle to the grooves in the opposite face, a series of type holding bars insertable in the grooves, each type holding bar having a pair of upwardly extending spring flanges extending above the surface of the type bed and a series of type positioned between the type holding bars and held in position on the type bed by the spring flanges thereof.

5. In a type bed, a flat bed having a series of parallel grooves in each of its opposite side faces, the grooves in one face lying at a right angle to the grooves in the opposite face, a series of type holding bars insertable in the grooves of either face, a series of type of a width for insertion between type bars in adjacent grooves and supported in place by the bars, and a series of type of a width which is a multiple of the distance between the bars of adjacent grooves whereby, through removal of one or more type bars,

such wider type will be held between the respective bars on opposite sides of the removed bar or bars.

6. In a type bed, a bed member formed of a moldable non-metallic material such as a rubber-like composition and having a series of spaced parallel grooves on its opposite faces, the grooves in one face being at an angle to those in the other face and providing ribs tending to sustain the body from flexing between the ribs under printing pressure, a series of sheet metal bars in-

sertable in the grooves of either face being sustained in position therein due to the spring of the metal maintaining tight engagement of the bars in the groove, the bars extending above the ribs of either surface when positioned therein, and a series of type positioned between adjacent bars, the grooves being spaced a distance apart to hold the type under pressure when positioned therebetween.
